Peabody, Mass., assignors to Nathan H. Poor
Company, Peabody, Mass., a corporation of
Massachusetts

Application June 15, 1939, Serial No. 279,252

2 Claims. (Cl. 34—160)

This invention relates broadly to a drying apparatus, and particularly to an apparatus for drying skins after the latter has received an application of a liquid coloring material.

It has been the custom in the past when seasoning, doping or coloring skins to apply the pigment or lacquer to said skins by any one of several methods. In certain instances the skin is placed upon a table having a glass or composition top, and the dope, pigment or lacquer is applied with a swab to the surface of the skin with one hand while holding said skin in place with the other hand. The skin is then removed from the table and suspended in a drying loft or in a mechanical drier. In other instances the skin is placed upon a screen in a booth and the finish is applied thereto with a spray gun, after which the skin is removed to a drier as previously described. In still other instances the skin is placed upon a conveyor belt and the finish is applied thereto by hand with a swab after which said skin is removed to a drier as previously described. In each instance the process is repeated as may be necessary, and in each instance much handling is required before the skin is finally finished.

The primary object of this invention is to provide an improved apparatus whereby a succession of alternate coloring and drying operations may be performed upon a skin while the latter remains permanently supported upon a conveying means.

Another object of the invention is to provide a means whereby a continuous stream of heated air may be directed against a skin in a manner to firmly hold the latter in position upon its supporting and conveying means while being subjected to the drying operation.

Another object of the invention is to provide an effective means of distributing the heated air over the surface of the skin and confining said air to an area adjacent to the moist surface of said skin.

Still another object of the invention is to provide a means whereby the drying instrumentalities may be moved transversely of the conveying means for the skins.

The invention consists of an apparatus for drying skins as set forth in the following specification and particularly as pointed out in the claims.

Referring to the drawings:

Fig. 1 is a side elevation of a drying apparatus embodying our invention, end portions of the conveying instrumentalities for the skins being broken away to save space in the drawings.

Fig. 2 is an enlarged detail side elevation of

the supporting structure for the air heating and distributing means.

Fig. 3 is an end view of the structure illustrated in Fig. 2.

5 Fig. 4 is an underneath plan view of an end portion of the discharge orifice for the drying air.

Fig. 5 is an enlarged central longitudinal section through a portion of the drying apparatus.

10 Fig. 6 is an enlarged transverse section taken on the line 6—6 of Fig. 5.

Like numerals refer to like parts throughout the several views of the drawings.

In the drawings, 10 represents a conveyor 15 frame having pulleys 11 and 12 mounted at opposite ends thereof upon which an endless conveyor belt 13 is mounted to travel through a horizontal plane in the direction indicated by the arrows appearing on Fig. 1. The pulley 11 is driven by an electric motor 14 through a suitable driving connection 15. The upper portion of the belt 13 is supported at regular intervals between the pulleys 11 and 12 by a plurality of small idler pulleys 16, while the lower portion of 20 said belt is supported by a plurality of idler pulleys 17, all of said idler pulleys being supported upon the conveyor frame 10. The pulley 12 is adjusted to tighten or loosen the belt 13 by means of and adjusting mechanism 18, and the working 25 face of said belt is cleaned during its return movement by a cleaning mechanism 19.

Located above the central portion of the conveyor belt 13, or at other locations as may be found desirable and as may be necessary where 30 more than one drying operation is to be performed, is a casing 20 which is suspended from above upon a plurality of I-beams 21. The casing 20 is formed of sheet material in units 22 secured together in any suitable manner to form 35 a continuous air chamber 23. Each unit 22 tapers toward the top thereof and is provided at 40 said top with an inlet orifice 24 for air. An annular steam radiator 25 of well known construction is mounted at the top of each casing unit 22 around the inlet orifice 24; and a fan 26 driven by an electric motor 27 is also provided at the 45 top of each casing unit 22, said fan being positioned in the inlet orifice 24. A lower portion of the casing 20 is formed with side walls 50 28 which converge downwardly to provide a narrow elongated discharge orifice 29 for the air which is forced through the casing units by the fans 26. The side walls 28 extend for the entire length of all of the casing units 22, and the 55 lower edges of said side walls terminate adjacent

to the working face of the belt 13. The discharge orifice 28 is continuous for the entire length of all of the casing units 22, and the air passing therethrough is discharged directly against the upper surface of skins 30 which rest upon said belt. The sides of the discharge orifice 28 converge at 31 toward the end of said orifice toward which the skins 30 are fed by the belt 13, see Fig. 4; and said skins are thereby subjected gradually to the influence of the stream of air passing downwardly through the discharge orifice to the end that the edges of the skins will not be lifted by air which has been deflected laterally because of contact with the belt. The lower edges of the side walls 28 are spaced apart at the discharge orifice 28 by a plurality of spacing members 32. After the heated air has been discharged from the casing 20 through the discharge orifice 28, said air is confined to an area adjacent to the working face of the belt 13 and the skins 30 thereon by means of plates 33 which extend for the entire length of the casing 20, inner edges of said plates being secured to the lower edge portions of the walls 28 of said casing, and the outer edges being supported by means of a plurality of rods 34 from an intermediate portion of the casing.

The casing 20 is suspended from the I-beams 21 by means of a plurality of supporting bars 35, lower ends of which are attached to said casing, and upper ends of which have yokes 36 secured thereto carrying rollers 37 which are arranged to roll upon lower flanges of said I-beams. Braces 38 are provided for the bars 35. The height of the casing 20 above the conveyor belt 13 may be varied as may be desired by manipulating the nuts 39 provided at the yokes 36.

The general operation of the apparatus hereinbefore specifically described is as follows: Skins 30 are placed upon the conveyor belt 13 at the left hand end thereof as viewed in Fig. 1, and operatives standing at the sides of said belt apply a liquid coloring material to the upper surface of said skins by means of a suitable swab while the skins are moving slowly with the belt toward the casing 20. As the skins pass successively beneath the end of the casing 20 they are subjected gradually to the influence of a stream of heated air which is discharged downwardly thereagainst through the V shaped portion of the discharge orifice 29 without there being any tendency for said stream of air to cause the edge portions of said skins to lift. The continued movement of the belt 13 will feed the skins into position to receive the full force of the stream of heated air passing through the narrow elongated discharge orifice 29, and the downward pressure of the jet of air contacting with the central portion of each skin will tend to hold said skin firmly upon the belt during the drying operation until they pass beyond the casing 20 whereupon they

may be subjected to another coloring operation. After being discharged from the orifice 29 the air is deflected laterally toward the sides of the conveyor belt and skins thereon, and said air is confined to an area adjacent to the upper surface of said skins as it passes thereabove by means of the plates 33.

It is evident that the conveyor apparatus may be of any length desired, and that there may be 10 any number of casings 20 provided as may be desired each provided with a suitable number of casing units 22 connected one to another and each provided with its separate heating and air distributing means. It is furthermore evident 15 that various types of heating devices may be utilized for heating the air as it passes through the drying units without departing from the spirit of this invention, and that under certain conditions the drying operation may be completed 20 without it being necessary to heat the air utilized. The casing 20 may be adjusted vertically above the conveyor apparatus as may be found desirable, and said casing may also be moved laterally of the conveyor by pushing thereon and causing the rollers 37 to roll upon the I-beams 21.

25 We claim:

1. An apparatus of the character described comprising, in combination, an endless imperforate conveyor belt to feed sheet material while having a liquid material applied thereto, a chamber for air provided with a narrow elongated discharge orifice for said air positioned above said conveyor belt and above and adjacent to the sheet material thereon, said discharge orifice extending longitudinally of said conveyor belt and tapering at and toward an end thereof, means to force air from said chamber through said orifice against the moistened surface of said sheet material, and means to raise and lower the air chamber.

40 2. An apparatus of the character described comprising, in combination, an endless imperforate conveyor belt for supporting and feeding skins and similar articles of sheet material while having a liquid material applied thereto, a chamber for air positioned above said belt and having a narrow elongated discharge orifice for said air extending longitudinally of said belt and positioned above and adjacent to the sheet material thereon, said orifice tapering at and toward an end thereof, means to heat said air, means to force said heated air from said chamber through said orifice against the moistened surface of said sheet material, means to confine said discharged air to an area adjacent to the sheet material as said air passes thereover, means to raise and lower the air chamber, a track and means to move said air chamber upon said track laterally of the conveyor belt.

69 NATHAN H. POOR, 2ND
SIDNEY G. JUDGE.
